CONDENSER

Joseph F. Sebald, Bloomfield, N. J., assignor to
Worthington Pump and Machinery Corporation,
Harrison, N. J., a corporation of Delaware

Application July 14, 1944, Serial No. 544,890

5 Claims. (CL. 261—115)

This invention relates to steam or liquid vapor condensers, and more particularly to a direct contact condenser which may be of the barometric type.

An object of the present invention is to provide a direct contact condenser which will provide controlled injection liquid distribution and a relatively unobstructed steam and vapor passage to the non-condensable gas or air cooler section of the condenser.

Another object of the present invention is to provide a condenser as specified wherein a novel type of surface producing means is provided which lowers the mass velocity in a given size of apparatus for a specific amount of work over the previous designs of barometric condensers.

With these and other objects in view, as may appear from the accompanying specification, the invention consists of various features of construction and combination of parts, which will be first described in connection with the accompanying drawings, showing a condenser of a preferred form embodying the invention, and the features forming the invention will be specifically pointed out in the claims.

In the drawings:

Figure 1 is a vertical section through the improved barometric condenser.

Figure 2 is a cross section taken on the line 2—2 of Figure 1.

Figure 3 is a cross section taken on the line 3—3 of Figure 1.

Figure 4 is a cross section taken on the line 4—4 of Figure 1.

Referring more particularly to the drawings, the improved condenser includes a shell 1 which may be cylindrical or any other desired shape but which provides an elongated interior space.

The shell 1 has an inlet pipe or tube 2 extending downwardly therein from its upper end and axially of the interior of the shell. This tube provides an inlet for the injection or condensing liquid, and it has a plurality of outlet nozzles 3 carried thereby and arranged in vertically spaced radially extending sets. In the drawings, the nozzles 3 are inclined so that the incoming water or condensing medium will be projected in thin streams of sprays radially and downwardly across the interior of the shell 1. Surface forming rings 4 and 5 are supported in any suitable manner within the shell and concentric of the axis of the shell and they have both their upper and lower ends open. These rings 4 and 5 form surface producing means against which the jet sprays of water or condensing liquid strike; the jets indi-

cated at 6 projected from the topmost sets of nozzles 3 engage against the inner surface of the shell 1. The impact of the jets of water or condensing liquid against either the inner surface of the shell 1 or the rings 4 and 5 produces a change in the directional flow of the water or condensing liquid and causes it to fall in substantially cylindrical curtains downwardly against and through the shell 1 towards the outlet 6 for mixed condensate and condensing liquid. The steam or vapor to be condensed enters the shell 1 through the inlet 7 and it is directed in an annular path by a cylindrical baffle 8 which is disposed concentrically of the axis of the shell 1, as clearly shown in Figure 4 of the drawings, to provide a uniform distribution of the steam into the shell, due to its decreasing cross sectional area as it recedes from the inlet 7. The upper edge of the eccentric baffle 8 is connected to the shell 1 by a horizontal shelf 9 and its lower end is open so that the incoming steam in the eccentric annular passage or space 10 will pass downwardly, then across the lower edge of the baffle and upwardly through the baffle as indicated in Figure 1 of the drawings. The steam passing across the lower edge of the eccentric baffle 8 will be contacted by and will flow through the downwardly falling, relatively fine streams of water or condensing liquid which are indicated at 11, and during its upward passage through the condenser shell 1, to the cooling space or cooler 12 for the non-condensable vapors, it will flow counter-current to the passage of the water or condensing liquid in the condenser and will flow not only through the downwardly falling, substantially cylindrical sheets of water but will flow across radially projected jets of water or condensing liquid issuing from the nozzles 3.

The cooler for non-condensable gases is formed by means of a suitable cylindrical shell or baffle 13 at the top of the shell 1, and it has its bottom open, while the top has a suitable outlet 14 for the non-condensable gases and uncondensed residual vapor. The tube 2 has a series of radially extending nozzles 15 carried thereby which are inclined with respect to the horizontal, and which project streams or sprays of water or condensing liquid radially and downwardly across the vapor cooler 12 and against the inner surface of the baffle 13 so as to provide a final condensing and cooling action by the coldest condensing liquid on the vapors which eventually reach the non-condensable vapor cooler 12.

A perforated distribution baffle 16 is disposed within the shell 1 between the lower open end of

the vapor cooler 12 and the uppermost set of nozzles 8. The water or condensing liquid sprayed into the vapor cooler 12 by the nozzles 15 falls upon the perforated distribution baffle 16 where it's distributed over the surface of the baffle and passes through the baffle in a plurality of fine stream which fall downwardly through the upwardly flowing steam or vapors to be condensed and across the radially projected jets.

By particular reference to Figure 1 of the drawings, it will be clear that the water or condensing liquid is projected both radially downwardly and in straight downwardly flow in such manner within the interior of the shell 1 that the vapors rising therein must pass a number of times through various jets or streams of the condensing liquid or water so as to provide maximum surface contact of the vapor and water to insure the efficient and complete condensation of the condensable vapors which are carried along with the water or condensing liquid as condensate to and through the outlet 6 and fully utilize the liquid by equally heating all of it. It is also clear that the large unobstructed flow area, while the steam is condensing, results in a decreasing velocity which minimizes the pressure drop from vapor inlet to the non-condensable vapor outlet. The lower end 17 of the shell 1 is shown as being substantially conical shape but inverted so as to guide the condensate and condensing liquid to the outlet 6. The liquid may be removed by any suitable means such as a pump or a barometric tube (not shown).

It will be understood that the invention is not to be limited to the specific construction or arrangement of parts shown, but that they may be widely modified within the invention defined by the claims.

What is claimed is:

1. In a direct contact condenser, a shell having a condensing medium inlet and an outlet for mixed condensate and condensing liquid, said shell having a vapor inlet disposed therein remote to the condensing liquid inlet whereby counter-current flow of vapor and condensing liquid will be set up within the shell, a plurality of nozzles in said shell for directing condensing liquid into the shell and across the flow path of the vapor, surface providing means in said shell, said surface providing means forming abutments against which the condensing liquid sprayed from certain of said nozzles strikes whereby the directional flow of the condensing liquid engaging the surface forming means is changed from a cross flow to a directional flow substantially parallel to the walls of the shell, and an eccentric baffle in said shell in the path of the incoming vapor to provide equal distribution of vapor in the shell.

2. In a direct contact condenser, a shell having a condensing liquid, said shell having a vapor inlet disposed therein remote to the condensing liquid inlet whereby counter-current flow of vapor and condensing liquid will be set up within the shell, a plurality of nozzles in said shell for directing condensing liquid into the shell and across the flow path of the vapor, surface providing means in said shell, said surface providing means forming abutments against which the condensing liquid sprayed from certain of said nozzles strikes whereby the directional flow of the condensing liquid engaging the surface forming means is changed from a cross flow to a directional flow substantially parallel to the walls of the shell, a non-condensable vapor cooler in said

shell, a plurality of nozzles for spraying condensing liquid into said vapor cooler, said vapor cooler provided with an outlet for non-condensable vapors, and a perforated distribution baffle between said vapor cooler and said first mentioned nozzles to direct the condensing liquid from the vapor cooler through the shell in a plurality of fine streams and direct the non-condensable vapors in a path across said fine streams during its flow to the vapor cooler.

3. In a direct contact condenser, a shell having a condensing medium inlet and an outlet for mixed condensate and condensing liquid, said shell having a vapor inlet disposed therein remote to the condensing liquid inlet whereby counter-current flow of vapor and condensing medium will be set up within the shell, a plurality of nozzles in said shell for directing condensing liquid into the shell and across the flow path of the vapor, surface providing means in said shell, said surface providing means forming abutments against which the condensing liquid sprayed from certain of said nozzles strikes whereby the directional flow of the condensing liquid engaging the surface forming means is changed from a cross flow to a directional flow substantially parallel to the walls of the shell, a non-condensable vapor cooler in said shell, a plurality of nozzles for spraying condensing liquid into said vapor cooler, said vapor cooler provided with an outlet for non-condensable vapors, a perforated distribution baffle between said vapor cooler and said first-mentioned nozzles to direct the condensing liquid from the vapor cooler through the shell in a plurality of fine streams and direct the non-condensable vapors in a path across said fine streams during its flow to the vapor cooler, and an eccentric baffle in said shell in the path of the incoming vapor to provide equal distribution of vapor in the shell.

4. In a direct contact condenser, a shell, a condensing medium inlet tube extending axially into said shell, a plurality of radially extending nozzles carried by said tube for directing the incoming condensing liquid in a plurality of jets across the flow path of vapor in the condenser, said shell having a vapor inlet disposed therein remote to the condensing liquid inlet whereby counter-current flow of vapor and condensing liquid will be set up within the shell, said shell provided with an outlet for mixed condensate and condensing liquid, and surface providing means in said shell, said surface providing means forming abutments against which the condensing liquid operated from certain of said nozzles strikes whereby the directional flow of the condensing liquid engaging upon the surface forming means is changed to a directional flow at acute angles to the flow of the condensing liquid from the nozzles, a non-condensable vapor cooler in said shell, a plurality of nozzles for spraying condensing liquid into said vapor cooler, said vapor cooler provided with an outlet for non-condensable vapors, and an eccentric baffle in said shell in the path of the incoming vapor to provide equal distribution of vapor in the shell.

5. In a direct contact condenser, a shell, a condensing medium inlet tube extending axially into said shell, a plurality of radially extending nozzles carried by said tube for directing the incoming condensing liquid in a plurality of jets across the flow path of vapor in the condenser, said shell having a vapor inlet disposed therein remote to the condensing liquid inlet whereby counter-current flow of vapor and condensing

liquid will be set up within the shell, said shell provided with an outlet for mixed condensate and condensing liquid, surface providing means in said shell, said surface providing means forming abutments against which the condensing liquid sprayed from certain of said nozzles strikes whereby the directional flow of the condensing liquid engaging upon the surface forming means is changed to a directional flow at acute angles to the flow of the condensing liquid from the 10

nozzles, a non-condensable vapor cooler in said shell, a plurality of nozzles for spraying condensing liquid into said vapor cooler, said vapor cooler provided with an outlet for non-condensable vapors, and a perforated distribution baffle between said vapor cooler and said first-mentioned nozzles to direct the condensing liquid from the vapor cooler through the shell in a plurality of fine streams.

JOSEPH F. SEBALD.
